COMBINATION VALVE

James K. Horne, Minneapolis, Minn., assignor to Minneapolis-Honeywell Regulator Company, Minneapolis, Minn., a corporation of Delaware

Application February 23, 1956, Serial No. 567,221

5 Claims. (Cl. 137—66)

This invention relates to combination valves of the type generally used in the control of gas heating systems. More particularly, the invention relates to a combined valve having a manually operable plug valve, a diaphragm valve, a pilot valve and a diaphragm controller valve wherein the last mentioned two valves are adapted to be energized by a very low voltage current, such as that generated by a thermopile heated by a pilot burner.

One of the objects of this invention is to provide a combination valve which provides all of the necessary valving functions required in a control system for a gas heating plant;

Another object of the invention is to provide a combination control which provides for the manual controlling of the gas flowing to a main burner and a pilot burner, provides an automatically controlled valve for the main gas flow, and provides a safety pilot valve for the pilot gas flow;

Another object of the invention is to provide, in a single control device, a control arrangement wherein the controller for the main gas flow and the pilot gas flow are each energized by the same power source so that the main gas valve is capable of opening only when the pilot gas valve is open.

Still another object of the invention is to provide a simple and inexpensive control device wherein the means for manually controlling the gas flow also provides means for resetting the safety valve which, in turn, indirectly controls the main valve;

A still further object of the invention is to provide an arrangement in a combination valve wherein the resetting means for the safety valve, which means also moves the main valve, does not require that the main valve be in a position preventing flow to the main burner while placing the safety mechanism and the pilot gas valve into their "on" positions and does not require, thereafter, manual movement of the main valve to its "on" position;

Still further objects of the invention will become apparent upon reading the following detailed description of the invention in conjunction with the accompanying drawing wherein;

Figure 1 is a vertical sectional view at a slight angle through the combination valve, along the line 1—1 of Figure 4 of the drawing;

Figure 2 is a sectional view along the line 2—2 of the upper two castings of the valve body;

Figure 3 is a sectional view of the lower casting of the valve body taken along the line 3—3 of Figure 5 of the drawing;

Figure 4 is a plan view of the control device with the top casting or cover removed and a portion of the intermediate casting broken away;

Figure 5 is a plan view of the lower casting of the valve body;

Figure 6 is a vertical sectional view through the lower casting, along the line 6—6 of Figure 5; and

Figure 7 is a schematic showing of the wiring dia-

2

gram of the control valve in a control system for a heating plant.

While the combination control device or valve is obviously readily adaptable to the control of various types of fluids, it will be described in its preferred embodiment as being used for the control of fuel gas in a heating system.

As can be best seen in Figure 1 of the drawing, the valve body consists of a lower casting 11, a middle or intermediate casting 12, and a top or upper casting 13. The three castings are adapted to be secured tightly together by means of a plurality of bolts 14 extending through aligned bores in the upper and intermediate castings and into a threaded bore 15 in the lower casting, with a sealing gasket and a diaphragm 17 between the intermediate and lower castings and a sealing gasket 18 between the intermediate and upper casting.

The lower casting has a threaded inlet 19 and a threaded outlet 20 with a transversely extending conical bore 21 opening into the inlet 19 and a partition 22 between the inlet 19 and bore 21 and the outlet 20. The partition 22 provides with the outer walls of the lower casting a passage 23 that starts at the outlet of the bore 21 and extends upwardly around the outlet passage 20 and terminates in an annular passage or chamber 23a in the upper surface of the lower casting. The annular chamber 23a forms a valve seat 24. A diaphragm 17, having a backing plate 25 secured thereto by means of a bolt 26, is adapted to co-operate with the seat 24 to control the flow of gas out of the outlet 20 and to a main burner M. A spirally coiled compression spring 27 is secured at its lower end to the backing plate 25 by means of the bolt 26. This spring reacts against the bottom of the intermediate casting 12 to normally bias the diaphragm 17 against the seat 24.

Positioned in the bore 21 is a cone-shaped, manually-operable plug valve 28 that is resiliently held in the bore 21 by means of a coiled compression spring 29 positioned in an axial bore 28a extending inwardly from the large diameter end of the plug valve. The spring reacts against a plate 30 secured to the outer surface of the casting 11 by means of bolts 31. The plug valve 28 has a transversely extending passage 28b therein which is adapted to conduct gas from the inlet 19 to the passage 23 when the plug valve 28 is in its "on" and "start" or "light pilot" positions but is manually rotatable to an "off" position to prevent the flow of gas therethrough. The plug valve is adapted to be rotated by means of a flat sided shaft 32 extending into a flat sided socket 28c formed in the small end of the plug valve. A control knob 33 is secured to the outer end of the shaft 32 by means of a snap ring 34 positioned in an annular groove near the outer end thereof and is held in assembled relationship with the plug valve by means of a snap ring 35 positioned on the other side of a cover plate 36 from the knob 33. The plate 36 is held against a side of the casting 11 by means of bolts 37. A groove 38 extends approximately half way around the plug valve and terminates at abutment shoulder 39 which serves a purpose to be hereinafter described. A radically extending arm 28d on the valve 28 co-operates with the ends of an arcuate groove 21a to stop rotation of the plug valve at its "off" and "start" positions.

The intermediate casting 12 has a recess 40 in the bottom surface thereof to form a pressure chamber over the diaphragm 17 when the two castings 11 and 12 are secured together. The casting 12 has a large recess 41 in the upper surface thereof in which is located a diaphragm-controlled valve and a pilot gas safety valve.

The diaphragm controller or supply and exhaust valve consists of a ball valve 42 positioned between a lower valve seat member 43 and an upper valve seat member

44. The valve seat members are retained in a threaded bore 41a by having the seat member 44 threaded into the bore 41a and into abutting engagement with the valve seat member 43. The opening 43a through the valve seat member 43 communicates, through a passage 45, with a threaded outlet or bleed port 46, which is adapted to be connected by a suitable conduit (not shown) to a bleed burner B on a pilot burner bracket (not shown), to conduct gas from the chamber 40 to the pilot burner P where the gas may be burned. A passage 47 extends from the chamber 40 to the space between the valve seat members 43 and 44 so as to make the chamber 40 in communication with either the outlet 46, as mentioned above, or the chamber 41 through a valve seat opening 44a in the member 44. The chamber 41 is constantly in communication with the chamber 23a through a bore 48 (Figures 4 and 5) extending from the chamber 41 near bore 69 to a transversely extending bore 49 communicating with the passage 23. It is thus seen that gas can flow from the outlet side of the plug valve 28 at all times to the chamber 41 so that gas can flow from the chamber 41 into the chamber 40 above the diaphragm valve if the ball valve 42 is in engagement with the valve seat 43a. If valve 42 is against the seat 44a, gas will bleed from the chamber 40 to reduce the gas pressure over the diaphragm and permit the inlet gas pressure to open the diaphragm valve.

The valve 42 is actuated through its stem 42a which, in turn, is connected to an armature lever 50. The lever 50 is made up of a pivoted member 50a of magnetic material, which has a downwardly struck portion 50b that is adapted to rock on a laterally extending arm 51a of a bracket 51. The bracket is secured to the bottom of the chamber 41 by means of a bolt 52 (Figure 4). The lever 50 is retained in proper alignment with a core 52 of an electromagnet by means of a steel plate 53 having a pair of L-shaped tines 54 positioned on opposite sides of the lever 50. Riveted to the arm 50a is a thin sheet of stainless steel 55 having notches 55a therein, adapted to receive the upwardly extending ends of the tines 54, to hold the lever 50 in proper pivotal relationship with the core 52. Downwardly struck detents 56 in the arm 50a engage in aligned holes in the member 55 to hold these two parts in proper alignment. An arm 57, also riveted to the arm 50a has a downwardly extending apertured portion 57a which receives the upper end of a coiled tension spring 58 which is anchored at its lower end to the free end of an adjustable lever 59. The member 57 has a forked end that registers with an annular groove in the upper end of the adjustable stem 42a and is retained in said annular groove by having a hole in the member 55 engage the upper end of the valve stem and hold it against longitudinal movement in the other member 57. The rivets through the members 55, 57 and 50a retain the valve stem in assembled relationship with respect to the members 55 and 57. The lever 59 is pivoted at its other end on a pivot 60 to the bracket 51. The lever is adjustable upwardly and downwardly by means of a screw 61 threaded into a threaded bore 62 in the bottom of the chamber 41. A coil 63 surrounds the core 52 and has one of its leads connected to a terminal member 65 and the other lead thereof connected to the terminal 67.

As can best be seen in Figure 1 of the drawing, flow of gas to the pilot burner P is controlled by a valve 68 adapted to seat over an outlet passage 69 communicating with a threaded outlet 70 which is adapted to receive a conduit (not shown) leading to the pilot burner. The valve is carried on one end of a lever 71, rockably mounted on a pivot 72. The pivot has its ends resting in slots 73 and 74 in the bottom of the chamber 41. The other end of the lever 71 carries an armature 75 that is adapted to be held by an electromagnet 76 but is incapable of being attracted thereby when the two coils 77 and 78 of the electromagnet, which are series con-

nected and mounted on separate legs of a horseshoe shaped core 79, are energized by a thermopile. Core member 79 is secured to a bracket or mounting arm 80 by means of a screw 81 and the arm 80 is, in turn, secured to the bottom of the chamber 41 by means of a screw 82. The valve 68 is normally biased to its closed position over the passage 69 by means of a coil compression spring 83 bearing at one of its ends against the lever 71, intermediate the valve 68 and the pivot 72, and bearing at its other end against an adjustable nut 84 on a swivelly mounted bolt 85 extending through a mounting plate 86. The mounting plate 86 is secured to two spaced bosses 87 and 88 by means of screws 89. One lead from one of the coils is connected to the terminal 67 while the other lead 91 from the other coil is connected to the terminal 92 located below the terminal 67. The coils 77 and 78 are electrically joined by a lead wire 93. A jumper wire 94 leads from the terminal 92 to a terminal 95 located below the terminals 65.

The valve 68 is adapted to be moved to its open position, with the armature 75 in engagement with the upper end of the core 79, against the bias of spring 83 by means of a stem 96 extending upwardly through a bore 97 in the lower casting 11 and a bore 98 in the middle casting 12. The lower end of the stem 96 is adapted to be engaged by the shoulder 39 on the plug valve 28 so that as the plug valve is rotated by the knob 33, from the "on" position a slight distance to the "pilot" or "light pilot" position, as indicated on the plate 36 by suitable indicia (not shown), the stem 96 will be raised to engage the lever 71 between the pivot 72 and the valve 68 and to open the valve 68. An annular abutment shoulder 99, formed on the stem 96 intermediate its ends, bears against an upper surface of the casting 11 in its retracted position, where it is resiliently held by means of a coiled compression spring 100. The spring is positioned between the upper surface of the abutment shoulder 99 and the shoulder formed by the junction of the large and small diameter bores of the step-bore 98. The spring 100 is sufficiently strong to return the plug valve and the control knob from the "pilot" position to the "on" position.

With the combination valve electrically connected into the heating system as shown in Figure 7, that is, with the inlet 19 connected to a source of gas supply, the outlet 20 connected to main burner M, the pilot burner outlet 70 connected to pilot burner P, the bleed outlet 46 connected to a bleed tube B, the terminal 65 connected by lead 101 to the fixed end of the room thermostat R, the terminal 95 connected by lead 102 to the other terminal of the room thermostat, the terminal 92 connected to one terminal of the thermopile T by lead 103, and the terminals 67 connected to the other terminal of the thermopile by a lead 104, the control system is ready to be placed into operation.

Operation

Assuming that the plug valve 28 is in its "off" position, that is with the large land portion of the plug valve positioned across the opening from the inlet 19, there can be no gas flow to either the main burner or the pilot burner. Under these conditions, there is no gas pressure in either the chamber 23a or in the chamber 40 below and above the diaphragm 18, respectively. Therefore, the diaphragm is resiliently held against the valve seat 24 by the spring 27. Also under these conditions, the thermopile is not generating any current, due to there being no flame present at the pilot burner, and the coil 63 is consequently de-energized causing the valve 42 to be in a position closing the bleed passage and permitting gas to have free access to the chamber 40. The coils 77 and 78 of the safety pilot valve 68 are also de-energized, causing valve 68 to be in its "closed" position. By rotating the plug valve 28 from its "off" position past its "on" position a

slight distance, to cause the shoulder 39 on the plug valve to lift the stem 96 against the bias of springs 100 and 83, the pilot valve 68 will be raised to its "open" position and the armature 75 lowered into engagement with the core 79 of the magnet 76. This will permit gas to flow to the pilot burner which may then be lighted. The gas will also flow to the chambers 23a and 40 simultaneously so the diaphragm valve will remain closed, thus preventing gas flow to the main burner during the relighting operation. After the hot junction end of the thermopile has been sufficiently heated by the pilot flame as to cause energization of the coil 77, releasing of the control knob 33 will permit the spring 100 to return the plug valve to its "on" position, as illustrated in Figure 3. The system is then under the control of the room thermostat. When the thermostat contacts close, the coil 63 is energized causing the valve 42 to move from the bleed seat to the supply seat and to vent the chamber 40 through the bleed tube B to the pilot burner. This causes the diaphragm valve to open and gas to be supplied to the main burner in a conventional manner.

Upon flame failure at the pilot burner, magnet 76 becomes de-energized causing closure of valve 68. Simultaneously, flame failure causes de-energization of coil 63 and movement of the valve 42 from the supply seat to the bleed seat to cause closing of the diaphragm valve. It is thus seen that de-energization of the thermopile T causes both the pilot valve and the main valve to become independently closed. It is also obvious that the main diaphragm gas valve cannot be moved to its "open" position unless there is a flame present at the pilot burner.

When it is desirable to shut down the heating system, it is only necessary that the control knob 33 be rotated to its "off" position where the passage 28b in the plug valve is out of registration with the inlet passage, which cuts off the pilot gas supply as well as the main gas supply.

From the above description, it can be readily seen that the combination valve supplies the entire valve needs of a heating system in a very compact unit. While I have described the preferred embodiment of the invention, it is deemed to be obvious to those skilled in the art that various modifications may be made in the invention without departing from the spirit thereof. Therefore, the scope of the invention is to be determined primarily from the appended claims.

I claim:

1. In a control device, the combination comprising a valve body having an inlet and a first outlet and a valve seat therebetween and a second outlet and a bleed port, a manually operable valve therein movable between "off," "on" and "start" positions and having an inlet connected to the inlet of said valve body and an outlet chamber

connected to the inlet side of said valve seat, a fluid pressure operated valve cooperable with said valve seat on the inlet side thereof and having a pressure chamber connected through a passage to the outlet of said manually operable valve and through a second passage to said bleed port, an electrically operated supply and exhaust control valve between said pressure chamber and said passages for controlling fluid flow to and from said pressure chamber, a movable wall between said pressure chamber and the outlet chamber of said manually operable valve for actuating the pressure operated valve in response to pressure differences on opposite sides of said movable wall, a manually-reset safety valve in said body connected to the outlet of said manually operable valve and to said second outlet, said safety valve having electrically energizable means capable of holding said safety valve in its "open" position but not capable of attracting it to its "open" position when said means is energized, and means including means on said manually operable valve for actuating said safety valve to its "open" position when said manually operable valve is moved from its "on" position to its "start" position, a single power source, both of said electrically operated valves being arranged so as to be energized by the said power source and so arranged that when they become de-energized the safety valve closes and the control valve moves to a position which supplies fluid to said pressure chamber to force the pressure operated valve to its closed position.

2. A control device as defined in claim 1, in combination with resilient means for automatically moving said manually operable valve from its "start" position to its "on" position when said means for actuating said manually operable valve is released.

3. The combination of claim 2, wherein said resilient means is located between said manually operable valve and said safety valve.

4. The control device as defined in claim 1, wherein said movable wall is a diaphragm.

5. A control device as defined in claim 1, in which the manually operable valve provides substantially full flow between its inlet and outlet when the valve is in its "start" position.
